APPARATUS FOR DRIVING PINS IN
BEDPOSTS

Elbert B. Hubbard, Sumter, S. C., assignor to Williams Furniture Corporation, Sumter, S. C., a corporation of South Carolina

Application May 13, 1941, Serial No. 393,223

5 Claims. (Cl. 1—6)

This invention relates to furniture manufacture and more especially to an apparatus for driving headless pins or nails into bed posts so that the bed side rails can be removably attached thereto. In the manufacture of bed posts, a longitudinal gap or slit is usually sawed in each post substantially at the elevation where the side rail is to be attached. Then suitable holes are bored transversely of the gap, and in each of these holes a pin which is slightly larger than the hole is inserted to a position where it will abridge the gap. Each end of the bed side rail has a plate member extending therefrom, which is adapted to be inserted in the gap. Also the plate member is provided with suitable hooks or notches which removably fit over the inserted pins when the plate member is inserted in the gap to connect the side rail to the post.

Heretofore, much difficulty has been encountered in quickly and accurately inserting the pins in the posts. Since the pins are headless it has been necessary to manually position the pins in the proper order prior to driving the same into the posts. The headless pins are unaligned in containers after manufacture, that is, packed in unstraightened position. In order to use these pins in the present mechanism, it is necessary to assemble them so that one or more pins at a time may be automatically withdrawn from the assembly and driven into the bed post.

It is therefore, an object of this invention to provide a machine of the character described having means for gathering unaligned headless pins and arranging them into straightened assemblies, in combination with a mechanism for withdrawing one pin at a time for each assembly and driving the same into a post.

Some of the objects of the invention having been stated, other objects will appear as the description proceeds, when taken in connection with the accompanying drawings, in which—

Figure 1 is a side elevation of my improved lock pin feeding and driving machine;

Figure 2 is a sectional plan view taken along the line 2—2 in Figure 1;

Figure 3 is a vertical sectional detail view taken along the line 3—3 in Figure 2;

Figure 4 is an elevation looking at the left-hand side of Figures 2 and 5;

Figure 5 is an elevation looking at the left-hand side of Figure 1;

Figure 6 is a sectional plan view through the pin receptacle and taken along the line 6—6 in Figure 1;

Figure 7 is a transverse vertical sectional view taken along the line 7—7 in Figures 1 and 6;

Figure 8 is a longitudinal vertical sectional view taken along the line 8—8 in Figure 6;

5 Figure 8A is an enlarged detail of a portion of Figure 8 showing the receptacle in a tilted position;

Figure 9 is an isometric detail view showing the lower portion of a pin chute, together with a pin feeding roller and a driving means for the pin;

10 Figure 10 is an exploded isometric view showing a bed post, a side rail and a pair of lock pins prior to being inserted in the post;

Figure 11 is a sectional detail view showing the post, side rail and lock pins in an assembled position.

Referring more specifically to the drawings, the numeral 10 denotes the framework of my improved pin feeding and driving apparatus. The upper portion of the framework (Figures 1 and 5) has a stationary mortised support 11 in which a tenon slide 12 is adapted to fit. This tenon slide is moved back and forth in the support 11 by means of a suitable hand wheel 13, which wheel is fixedly secured upon one end of a rod 14. The rod 14 has its intermediate portion rotatably mounted in the support 11 as at 15 and has the end remote from the wheel threadably secured in a suitable projection 16, said projection extending upwardly from the base of support 11. By turning the hand wheel 13, the tenon slide 12 is moved back and forth relative to the framework 10 and support 11.

Upon the slide 12 a suitable table member 17 is mounted. This table member supports a horizontally disposed plate member 18 by means of suitable bolts 19 and 20. The bolts 19 have the upper ends thereof secured to the bottom of plate 18 so that the intermediate portions will penetrate holes 19a in table member 17. Nuts 19b are threadably mounted on the lower ends of the bolts at points below the table member. The bolts 20 have the intermediate portions thereof threadably mounted in table member 17 so that the upper ends will support plate member 18 and hold nuts 19b against the lower side of the table 17. The height of the plate member 18 may be adjusted by manipulating these bolts.

The top edge of the plate member 18 is adapted 50 to rest against the bottom of a suitable filler member 21, which filler member is also carried by the table 17. In other words, the right hand face of filler member 21 (Figure 1) and the upper face of plate member 18 are disposed substantially at right angles to each other, thereby providing an

L-shaped recess into which a suitable workpiece such as a bed post 23 is adapted to be placed. By observing Figure 2, it will be seen that a suitable stop 24 is provided, near the left hand end of filler member 21. This stop serves as a guide against which the ends of posts 23 are adapted to rest when placed in position on the table, thus insuring that each post will occupy the same position.

Referring to Figures 10 and 11, it will be seen that post 23 is provided with a suitable longitudinal arcuate gap 27. This gap is adapted to have suitable holes 28 extending at right angles to the plane of the gap and being aligned with each other. Usually these holes are of a slightly smaller diameter than the pins so as to insure that once a pin has been inserted, it cannot be easily removed. When the pins 29 are inserted in the holes 28 to a position where gap 27 will be bridged, suitable notches 30 in side rail plate 31 are adapted to removably fit over the pins. Plate 31 extends from a side rail 32 which forms a part of the bed structure.

After the holes 28 and the gap 27 have been provided, the post 23 is positioned upon the table support 18 in the manner shown in Figures 1, 2 and 9 so that one end thereof will abut the stop 24. When in the proper position, the holes 28 will be disposed opposite plungers 35, which plungers form an integral restricted portion of shafts 36. Each shaft 36 and its associated plunger 35 is mounted for reciprocation in a suitable block or bearing 37. The block 37 is provided with grooves 38, each of said grooves 38 being aligned with a plunger 35 and being adapted to receive pins 29 during the operation of the machine. The plungers 35 and shaft 36 are reciprocated in a manner hereinafter to be described to cause the pin 29 (Figure 9) to be moved from the position shown, into the holes 28 in post 23. It should be noted that the pin 29 will be moved far enough into the hole 28 to cause the same to abridge the gap or slot 27 thereby forming a lock pin over which notches 30 in side rail plate 31 are adapted to fit when the parts are in assembled position as shown in Figure 11.

Pin driving mechanism

The plungers 35 and associated enlarged portions 36 are adapted to reciprocate in bores 39 in bearing block 37 (Figures 1, 2 and 9). The enlarged portions 36 are also mounted for reciprocation in another bearing 40, and the ends of both enlarged portions 36 are connected as at 41 to a link 42, said link 42 being pivotally secured as at 43 to a rotary disk 44. The point 43 is eccentrically located relative to a shaft 45 upon which the disk is secured. Shaft 45 is rotatably mounted in bearings 48 and 49 which, in turn, are supported by the framework 10. On the other end of shaft 45, a suitable wheel 50 is fixedly secured, upon which a belt 51 is mounted, said belt being also mounted upon another wheel 52 (Figure 4) loosely mounted around a shaft 55. The shaft 55 extends into gear reduction unit 56 (Figure 1). Another shaft 57 projects from the gear reduction unit and is connected as at 58 to a shaft 59 of a motor 60.

Clutch mechanism

In order to connect the shaft 55 with the loose wheel 52, a suitable clutch mechanism is provided. Wheel 52 has an annular drum 61 and the interior periphery of this drum has suitable shoes 62 contacting the same, said shoes being

5 segmental in shape, and being separated by suitable bolts 63 loosely extending from the inner ends of levers 64. Levers 64 are pivoted intermediate their ends as at 65 to opposed sides of a hub 66, which hub is also keyed upon shaft 55. It will be noted that the shaft 55 has a hub 68 slidably keyed thereon, said hub having a peripheral groove 69 therein, and also having a conical cam surface 70 on one of its ends. This conical surface is adapted to be moved inwardly beneath the ends of levers 64 when it is desired to expand the shoes 62 against the inner periphery of drum 61, and thereby connect the rotating shaft 55 with the loosely mounted wheel 52.

10 The means for manipulating the hub 68, inwardly and outwardly relative to the wheel 52, comprises a lever 75 having a forked end 76 fitting astride the grooves 69. Lever 75 is pivoted intermediate its ends as at 78 (Figures 2 and 5) to the framework 10. The other end of the lever 75 has pivoted thereto as at 79, a link 80 the other end of which is pivoted as at 81 to the vertical leg of a bell crank 82, said bell crank being pivoted as at 83 to framework 10. The horizontal leg of the bell crank has pivoted thereto as at 84, a vertically disposed link 85. This link extends downwardly and has pivotally connected to its lower end as at 86, an operating foot lever 87, said lever 87 extending beneath the machine and having one of its ends pivotally connected as at 88 to the framework 10.

15 Upon applying pressure to the free end of lever 87, the link 85 is pulled downwardly and bell crank 82 is thereby rotated in a counterclockwise manner in Figure 5. This movement will move the link 80 to the left in Figure 2, and rotate the lever 75 in a clockwise manner about pivot point 78 to cause the conical portion 70 to move inwardly toward the hub 66. The inward movement of the conical portion will expand the left-hand ends of levers 64, causing them to rotate about their respective pivot points 65 to expand the shoes 62 against drum 61. When the shoes are properly expanded the rotating hub 66 is connected to wheel 52 to impart movement to various elements of the machine.

20 If it is desired to cause the wheel 52 to be disconnected from the motor 60, it is necessary to release the foot pedal 87 to allow spring 87a to pull the same upwardly. The upward movement of the pedal will move the hub 68 outwardly, that is to the left in Figure 2, thereby relieving the pressure of shoes 62 on the interior periphery of drum 61.

Pin stacking and feeding mechanism

25 A pair of shafts 90 are rotatably mounted in bearing 37. The end of each shaft has fixedly secured thereon a disk member 91 and the periphery of this disk has a groove 92 therein substantially of the same size as the diameter of a pin 29. The axes of rotation of shaft 90 and disk 91, and the longitudinal axis of groove 92 are substantially parallel to the path of reciprocation of plunger 35. The shaft and disk, however, are off-set relative to the notch 38 (Figures 5 and 9). As the disk rotates, a pin 29 falls from 30 a chute 93 into the groove 92. Upon further rotation of the disk, the pin 29 will be delivered to the notch 38 at a point in advance of the plunger 35. In other words, as disk 91 rotates in the direction of the arrow in Figure 9, the lowermost pin 29 in the chute 93 will fall into peripheral

groove or notch 92. This pin will be carried around as the disk 91 rotates, and when the notch 92 begins to move downwardly the pin 29 will fall therefrom into the notch 38, after which the plunger 35 will move toward the observer in Figure 9 to press the pin 29 into hole 28 in the bed post 23. After the plunger 35 has moved the pin 29 into the proper position in hole 28, the direction of movement of the plunger is reversed, until it moves substantially to the position shown in Figure 9. At the same time, the disk 91 rotates again to a point where the groove 92 will receive the next lowermost pin 29 from the chute 93. The operation will again be repeated for the succeeding bed posts 23.

The upper portion of the chute 93 is flared outwardly as at 93a so that the pins 29 will more easily fall therein as they are expelled from a suitable receptacle 96, through an opening 97. The function of the receptacle 96 and its associated parts will be later described.

Driving connection for disks 91

Each of the shafts 90 has a sprocket 93 on one end thereof. Upon these sprockets a suitable chain 100 is mounted, said chain also being mounted upon other sprockets 102 and 103 on shaft 104 and pivot 105 respectively (Figures 2 and 3). The shaft 104 is rotatably mounted in bearing 110, said bearing being supported by the framework 10. Shaft 104 also has fixedly secured thereon a beveled gear 111 which meshes with another beveled gear 112 on a shaft 114, said shaft 114 being rotatably mounted in bearings 115 and 116. The intermediate portion of shaft 114 has a sprocket 117 fixedly secured thereon upon which a chain 118 is mounted, and this chain is also mounted upon another sprocket 119 on shaft 45, previously described (Figures 1 and 4).

As the shaft 45 rotates, to cause the pin driving plungers 35 to reciprocate back and forth, the sprocket 119, chain 118, sprocket 117, shaft 114, bevelled gears 111 and 112, shaft 104, chain 100, and sprockets 99, 102 and 103 are caused to rotate. This rotation will cause the shafts 90 and attached disks 91 to also rotate. It is therefore seen that the pin feeding mechanism is driven in timed relation to the pin driving mechanism because both the feeding and driving mechanisms are driven from shaft 45.

Oscillating pin receptacle

By referring to Figures 1, 6, 7 and 8 it will be seen that the pin receptacle 96 is pivotally secured to the upper end of chutes 93 as at 125. This receptacle has a suitable cover 126 hingedly secured to the upper side thereof as at 127, the free end of which is held in closed position by a latch 128. In ordinary operation the headless pins 29 are dumped indiscriminately into the receptacle 96, and then the cover is latched in closed position.

When the machine begins operation, the receptacle is oscillated back and forth about hinge point 125 from dotted line to bold line position in Figure 1. This movement will cause the headless pins to move endwise out of the receptacle through the openings 97 into chutes 93. The reason for the pins moving in such a manner into the chutes is due to the special bottom construction of the receptacle 96. The bottoms of the receptacle are V-shaped and are designated by the reference characters 130. The lower portion of each V-shaped bottom leads directly into

an opening 97. The base of the bottom has a suitable V-shaped angle member 131 fixedly secured therein, which also leads to opening 97. It should be noted that the flanges of the angle member 131 rest upon the inwardly inclined bottom 130, thereby causing the upper edges of these flanges to serve as stops to prevent the pins on the inclined bottom 130 from crowding the pins which are disposed in the base of the V-shaped angle member 131. By referring to Figure 6, it is seen that the pins 29 fall in longitudinal alignment when disposed in the base of the angle member 131. At the same time, the pins which rest on the inclined sidewalls of the bottom 130 abut the upper edges of the angle flanges and are prevented from crowding the aligned pins in the angle member.

As the receptacle 96 is rocked back and forth, the pins in the base of angle members 131 are fed endwise from the receptacle 96 through the openings 97 and into the chutes 93, where they fall in superposed position, that is, one upon the other. Each time the receptacle rocks to dotted line position one or more headless pins are fed from each angle 131 through an opening 97. The edges of angle members 131 serve to align the pins as they travel towards the bottom of the angles 131 and on to the discharge position.

Means for oscillating receptacle 96

The free end of the receptacle 96 (Figure 1) has pivoted thereto as at 135, a link 136, said link having its lower end pivoted as at 137 to one leg of a bell crank 138. The bell crank has a second link 139 pivoted to its other leg as at 140, which second link is pivoted as at 141 to an upstanding lever 142. Bell crank 138 is pivoted as at 138a to framework 10. The lower end of the lever 142 is fixedly secured upon a shaft 143, which, in turn, is mounted for oscillation in bearings 144 and 145 on framework 10. Shaft 143 also has fixedly secured thereon a downwardly extending lever 146 (Figure 4) the lower end of which is secured to link 147 as at 148. The other end of link 148 is pivotally secured as at 149 to wheel 50. Since the point 149 is eccentrically located relative to the axis of rotation of wheel 50, it is seen that the link 147, arm 146 and shaft 143 will be oscillated back and forth as the wheel 50 rotates. This oscillation of the shaft 143 will produce oscillation of lever 142, link 139, bell crank 138, which in turn will oscillate the receptacle 96 about the pivot point 125. By providing an apparatus of this type, the headless rivets can be indiscriminately dumped into the receptacle 96 and as this receptacle oscillates, the pins will be expelled therefrom in aligned position and caused to fall into the chutes 93 in a superposed position.

In the drawings and specification, there has been set forth a preferred embodiment of the invention, and although specific terms are employed, they are used in a generic and descriptive sense only and not for purposes of limitation, the scope of the invention being set forth in the appended claims.

I claim:

1. In a machine for driving headless pins into members such as posts and the like, a rotary wheel mounted on a horizontal axis, said wheel having an open slot in its periphery, a pin receiving chute disposed above said wheel whereby the lowermost pin in the chute will fall sidewise into said slot upon each revolution of the wheel, and fall out of the slot when it reaches lowermost position, a pivoted receptacle for holding

unalined headless pins, said receptacle having an opening therein through which pins are adapted to successively pass into said chute, means for oscillating said receptacle to cause the pins to pass through said opening and into said chute, said receptacle having a V-shaped bottom the lowermost portion of which is in alinement with the opening therein whereby the pins will be placed in parallel position prior to their emerging through the opening into the chute.

2. In a machine for driving headless pins into members such as posts and the like, a rotary wheel, said wheel having an open slot in its periphery, a pin receiving chute disposed above said wheel whereby the lowermost pin in the chute will fall into said slot upon each revolution of the wheel, and fall out of the slot when it reaches its lowermost position, a receptacle for holding unalined headless pins and being pivoted at its end near the chute, said receptacle having an opening therein through which pins are adapted to successively pass into said chute, means for oscillating said receptacle to cause the pins to pass through said opening and into said chute, said pivoted receptacle having a V-shaped bottom, an angle iron member secured in the lowermost portion of the V-shaped bottom and conforming with the angularity of the bottom, whereby the pins will be straightened by coming in contact with the edges of the angle iron and will then move into the lowermost portion of angle iron member prior to their emerging from said opening.

3. In a machine for driving headless pins into members such as posts and the like, means for automatically positioning a headless pin endwise at a point in the machine, a pin receiving chute disposed above said positioning means, means for selecting the lowermost pin from said chute, a pivoted receptacle having an opening therein through which pins are adapted to successively pass into said chute, means for oscillating said receptacle to cause the pins to pass through said opening into said chute, said pivoted receptacle having a V-shaped bottom, an angle iron member

secured in the lowermost portion of the V-shaped bottom and conforming with the angularity of the bottom, whereby the pins will be straightened by coming in contact with the edges of the angle iron member and will then move into the lowermost portion of angle iron member prior to emerging from said opening.

4. Feeding mechanism for pin driving machines comprising a chute, a hopper pivoted to 10 the upper end of said chute and having an opening therein substantially coinciding with the chute, said hopper being adapted to receive unalined headless pins, and means for oscillating said hopper about its pivot to thereby cause pins 15 to slide from the hopper through said opening and into superposed alinement positioned within the chute, said hopper having a V-shaped bottom provided with an angle iron member in the lowermost portion of the V-shaped bottom and extending to said opening, whereby oscillation of the hopper will cause the pins to strike against the edge of the angle iron member to aline the same prior to their moving into the lowermost position of the angle iron member.
- 20 5. In a device for alining pins, a hopper having its bottom inclined inwardly and downwardly from the lower edge of each sidewall, thereby forming a V-shaped groove in said bottom, one of the endwalls having an opening coinciding 25 with the bottom of the V-shaped groove and being of a size to allow only one pin at a time to pass therethrough, said hopper being adapted to have a mass of unalined pins dumped therein, said hopper being pivoted intermediate its ends, 30 means for oscillating said hopper to aline the pins in the V-shaped bottom and to expel the alined pins from said hopper through said opening in one end of the hopper, the V-shaped groove having an angle iron in the same conforming to the 35 bottom of the hopper and against the edges of which the pins will strike and become alined during oscillation of the hopper.
- 40

ELBERT B. HUBBARD.
